UNITED STATES PATENT OFFICE.

WILLIAM A. FOSS, OF CLEVELAND, OHIO, ASSIGNOR TO THE AMERICAN TOLL TELEPHONE COMPANY, OF SAME PLACE.

DESIGN FOR A CASE FOR SLOT-TELEPHONES.

SPECIFICATION forming part of Design No. 33,593, dated November 20, 1900.

Application filed June 22, 1900. Serial No. 21,243. Term of patent 7 years.

To all whom it may concern:

Be it known that I, WILLIAM A. FOSS, a citizen of the United States, residing at Cleveland, in the county of Cuyahoga and State 5 of Ohio, have invented and produced a new and original Design for a Case for Slot-Telephones, of which the following is a specification, reference being had to the accompanying drawings, forming part thereof.

50 In the drawings, Figure I is a perspective view of a case showing my design. Fig. II is a front side elevation of the same. Fig. III is a left-hand side elevation.

55 My design comprises a front 5, having an external rough surface, and the sides 6 and 6 of the case are, in the main, vertical and parallel and curve at their lower ends, as at 7, inwardly and toward the bottom. The top of the case has its central portion 8, that is arranged centrally between the sides 6 and 6, extending upwardly above the side portions of the top and rounded. The central portion 8 of the top at each side terminates in a concavity or depression 9, that extends from the 60 front to the rear of the case, and the outer side wall of each depression 9 swells or curves outwardly, as at 10, and forms the upper end of the adjacent side 6 of the case. Each 65 side of the top curves inwardly, therefore, between the central portion of the top and the upper end of the adjacent side of the case.

70 The sides and top of the case are smooth and terminate at the rear end of the case in

an external flange 11, that slopes rearwardly 35 and outwardly from the top and sides.

A case having the configuration hereinbefore described is symmetrical and attractive.

The edges 12 of the front are flush with the sides and top and form a forward extension 40 of the said sides and top. The front at its edges is flanged forwardly, so as to form a rim or border 13 for the front, and the said rim is smooth, so as to contrast with the rough surface of the front.

45 The essential and characteristic features of the design are not only the rounding or curving of the upper ends of the sides toward the top and the peculiar configuration of the top so as to form the central raised and rounded 50 portion 8 and the depressions 9 and 9 at opposite sides, respectively, of the said central portion 8 and the rounding or curving of the outer side walls of the said depressions, as at 55 10, but the curving of the lower ends of the sides, as at 7, inwardly and toward the bottom, so as to produce a design that is symmetrical and attractive.

What I claim is—

60 The design for a case for slot-telephones, substantially as hereinbefore shown and described.

Signed by me at Cleveland, Ohio, this 19th day of June, 1900.

WILLIAM A. FOSS.
